[57] CLAIM

The ornamental design for spectacles frame front, as shown.

DESCRIPTION

FIG. 1 is a front elevational view of the spectacle frame front showing my new design;

FIG. 2 is a left side elevational view thereof;

FIG. 3 is a top plan view thereof;

FIG. 4 is a right side elevational view thereof;

FIG. 5 is a rear elevational view thereof; and,

FIG. 6 is a bottom plan view thereof.

The broken line showing of the eyeglass temples in FIGS. 1-6 is for illustrative purposes only and forms no part of the claimed design.
